DEEP WELL PUMP APPARATUS

Albert G. Bodine, Jr., Van Nuys, Calif.

Application March 8, 1948, Serial No. 13,695

9 Claims. (Cl. 103—1)

1

This invention relates generally to deep well pumps, and more particularly to improvements in deep well pumps operated by periodic waves of tension and compression at sonic frequencies in an elastic column such as the pump tubing or a rod string.

The present application discloses improvements in a certain class of pumps broadly disclosed in my copending application entitled Method and Apparatus for Pumping, Serial No. 761,456, filed July 17, 1947, and allowed October 22, 1947, now Patent No. 2,444,912. In said application I disclosed several embodiments of the type of pump to which the present invention broadly pertains, including forms in which the wave motion is transmitted down an elastic tubing, and other forms in which the wave motion is transmitted down an elastic rod string. Taking the first class as representative, the elastic tubing may typically be suspended from a spring-mounted platform at the ground surface. An eccentrically weighted flywheel is mounted in bearings supported on the platform and serves, when driven at high rotational velocity, to longitudinally reciprocate the upper end of the tubing in such a manner as to transmit down it alternate deformation waves of tension and compression. Points along the tubing are thus set into vertical oscillation. Preferably, the waves are generated at such a frequency relative to the length of the tubing that the tubing is resonated and there is produced therein, in a manner well known to those familiar with the acoustic art, a standing wave characterized by alternate regions of maximum and minimum oscillatory movement. A fluid impelling the check valve means is mounted in the tubing, preferably at a point of maximum oscillatory movement (velocity anti-node) and participates in the vertical oscillations of the portion of the tubing in which it is mounted, whereby increments of fluid are pumped upwardly past the check valve to be elevated in the tubing. Additional fluid impelling and check valve means may advantageously be located at other velocity anti-nodes in the tubing, as explained in my said earlier application.

In such a pump it is unavoidable that the elastic waves generated at the ground surface become attenuated and lose some of their power as they progress down the pump tubing. These losses result not only from friction within the tubing material as it is flexed by the passage of the wave, but also from friction between the tubing surfaces and the well liquid, and at some points through contact with the walls of the well hole.

Since the usual well tubing is uniform in its wave transmission characteristics throughout its length, the attenuation of power results in a re-

2

duction in displacement amplitude of the check valve near the bottom of the well. The pumping efficiency may be thus considerably impaired. With a pump tubing having a number of check valves, as mentioned above, the quantity of liquid pumped will be somewhat limited to that displaced by the check valve having the least movement, especially if such valve be at the intake end. For instance, the check valve located at 10 the lowest point in the well may receive a vertical oscillation which is less than one-half the oscillation of check valves near the surface.

It is one of the major objectives of the invention to overcome the disadvantages of power attenuation in such pumps. The achievement of this object is made possible by the fact that the displacement amplitude at any point along the tubing for a wave of given power will be inversely proportional to the longitudinal dynamic stiffness of the tubing in that region. If the tubing is relatively stiff under conditions of wave propagation, that is, if the ratio of periodic longitudinal stress at a given section of the tubing to the oscillation velocity at that section is very high, the transmission of elastic waves of a given power will produce a relatively small longitudinal displacement amplitude. In the language of the acoustic art, such a tubing is said to have a high acoustic impedance. If, on the other hand, the longitudinal dynamic stiffness of the tubing is relatively small, that is, the ratio of longitudinal periodic stress at a given section to the oscillation velocity at that section is relatively low, the transmission through 30 the tubing of a wave of the same power will produce a relatively large longitudinal displacement of each section of the tubing. In the language of the acoustic art, such a tubing is said to have low acoustic impedance.

40 Broadly speaking, the primary object of the invention is accomplished by employing a tubing section of relatively high impedance in the upper portion of the well and a tubing section of substantially lesser impedance in the lower portion 45 of the well. In a deep well, I may employ a long stand of tubing in which the impedance diminishes from section to section throughout its length; having the maximum at the upper end and a minimum at the lowest section. For reasons that should now be evident, the wave increases in amplitude each time it leaves an upper tubing section of one acoustic impedance and enters a lower tubing section of reduced acoustic impedance.

55 However the invention is not restricted to mere compensation of wave impairment owing to power attenuation along the elastic column. On the contrary, it is a further purpose and accomplishment to use a column section of reduced

impedance at the lower end to increase the pumping stroke substantially above what would be achieved where there is no attenuation to contend with. In other words, it is a further object of the invention to provide the pump with an elastic column whose lower or pumping end will oscillate at greater amplitude than will its upper or power receiving end.

The invention is not limited to any particular means for diminishing the impedance of the tubing. A rigorous expression for the desired reduction of uniformly distributed impedance would state that the mathematical product of mass per foot times the speed of sound along the member should be reduced in order to reduce the impedance. This may be accomplished, for instance, by reducing the wall thickness of the tubing in the lower part of the well, or by using a material having a lower modulus of elasticity, or both, or in any other way in which the ratio of longitudinal dynamic load to the longitudinal deformation particle velocity of the tubing is diminished. For some special cases it may be desirable to reduce the relative modulus by forming the lower portion of the pump tubing in "accordion" fashion, or by making other special arrangements for reduction in the acoustic impedance of the tubing. Moreover, the wave motion may be transmitted to the pumping member in the bottom of the well via an elastic column other than the tubing, for example, via a string of sucker rods.

The invention will be better understood from a consideration of several illustrative embodiments thereof, reference for this purpose being had to the accompanying drawings, in which:

Figure 1 is a partly elevational and partly longitudinal sectional view of one embodiment of the invention;

Figure 2 is a longitudinal sectional view of a desirable means for coupling two tubing lengths of differing wall thickness;

Figure 3 is a view partly in longitudinal medial section, and partly in elevation, of another embodiment of the invention;

Figure 4 is an enlarged longitudinal sectional view of the lower end portion of the pump of Figure 3; and

Figure 5 is a partly elevational and partly longitudinal sectional view of another embodiment of the invention.

In Figures 1 and 2 an oil well bore is indicated by the letter W, and a well casing within said bore by numeral 10, the lower end portion of the casing adjacent the productive formation being understood to be perforated in the usual manner. The stand of tubing 11, understood as composed of elastic material, as steel, is suspended in well bore W from platform 12, its lower end reaching downwardly to the region of liquid L to be pumped from the well bore. Tubing 11 is formed in pump tubing sections of usual lengths coupled together as by use of conventional coupling collars, such as C. Platform 12 is resiliently mounted on vertical coil springs 13 standing on platform 14 which is in turn supported on the ground surface. The lower end portion of the tubing 11 is controlled by a check valve 15, and its upper end has delivery pipe 15a.

Mounted on platform 12, or on the upper end of tubing 11 extending thereabove, is a housing 16 containing a means for vertically vibrating the platform 12, and thereby exerting a vertical oscillating force upon the upper end of the tubing 11. The means for generating vibrations con-

tained within housing 16 may be mechanical, electrical, hydraulic, or of any other type capable of delivering sufficient power. Since the vibrating means is employed to generate elastic waves in the pump tubing which are of the same nature as sound waves, and travel with the speed of sound waves in the medium of the pipe, I may properly refer to the vibratory generator means as a sound or sonic wave generator G. A sound wave generator well adapted for this purpose is described in my copending application Serial No. 761,456, and the one illustrated in Figure 1 of the present case is of that general type, having meshing oppositely rotating spur gears 17 carrying eccentric weights 18 which balance out horizontal vibrations but are additive to produce a substantial resultant oscillatory force in a vertical direction. The driving pulley of the sound wave generator G, mounted on the shaft for one of the spur gears, is driven by electric motor 19 through belt 20.

The oscillating force applied to the upper end of the elastic tubing 11 by sound wave generator G causes the upper end portion of the tubing to be alternately elongated and shortened. These deformations of the elastic tubing cause alternate waves of tension and compression to be launched down the tubing, traveling in the material of the tubing with the speed of sound, and hence being referred to as sound waves. It must be understood that the tubing is not vertically reciprocated in a bodily manner. On the contrary, the vertically oscillating forces applied to the upper end of the tubing by the generator G are of such high frequency (for instance, though without implying any limitation on the invention, 20 cycles per second for a 4,000 ft. tubing) as to make that type of operation impossible. Instead, longitudinal elastic deformation waves of compression and tension, of wave length usually shorter than the length of the tubing, travel down the tubing, causing each transverse section thereof to oscillate vertically with each passage of a wave. Since the frequency is such as compared with the length of the tubing as to provide a wave length along the tubing which is short relative to the length of the pipe, vertically spaced portions of the tubing may actually be traveling in contrary directions at a given instant. For purposes of maximum efficiency, it is desirable that the frequency of the sound wave generator and the length of the tubing should be so related that the tubing stand is longitudinally resonated, which is accomplished by driving the sound wave generator at a resonant frequency of the tubing string. Such operation establishes a standing wave along the tubing, with one or more velocity nodes at tubing sections a half-wave length apart. At these tubing sections, the amplitude of vertical oscillation is substantially zero. At points half-way between these velocity nodes there will appear regions of maximum amplitude of vertical oscillation. For the purpose of the embodiment of Figure 1, it is desirable to have the check valve 15 at a point of substantial or maximum oscillation, and hence it is desirable, though not essential, to establish a velocity anti-node region near or at said juncture.

The tubing 11 thus undergoes vertical oscillation in amounts which may differ from section to section along its length. If the valve 15 is located at a velocity anti-node, the amplitude for this vertical oscillation will be maximized at the location of the check valve. During each oscillation of the check valve 15, a small incre-

ment of well fluid travels upwardly in the pump tubing past check valve 15, to be elevated in the pump tubing and eventually discharged via a delivery tube indicated at 22. Considering the check valve 15 in more particular, it comprises typically a valve seat ring 23 rigidly secured within the pump tubing, said ring having passageway 24 whose top end forms a seat for check valve ball 25. Functionally considered, this check valve consists of a fluid impelling and check valve means operated by the described vertical oscillations of the portion of the pump tubing to which the ring 23 is secured. On each down stroke of the ring 23, occurring with an acceleration exceeding gravity, a small increment of well fluid is displaced thereby to flow upwardly through passageway 24 and past the unseated valve ball 25 to the liquid column thereabove, it being understood that the check valve ball 25 will descend at a slower rate under the acceleration of gravity than will the valve seat ring 23 driven by the oscillating pump tubing, so as to open the passage 24 on the down stroke of said ring 23. Further, the described down stroke of the ring 23 tends to leave a void in the liquid column thereabove, which has the effect of causing well fluid to be sucked upwardly through the passage 24. On the succeeding upstroke of the valve seat ring 23, the valve ball 25 seats at the upper end of passage 24, and the entire liquid column above is elevated accordingly. This operation is more fully discussed in my aforementioned prior application Serial No. 761,456.

The vertical displacement amplitude of any given section of the pump tubing will be determined by the stiffness or impedance of the tubing in that region. Since the upper portion of the pump tubing must carry the entire weight of the tubing stand hanging below, it is necessarily relatively thick-walled and stiff, its impedance is high, and the displacement amplitude is therefore small. Moreover, since the power transmitted down the pump tubing must inevitably experience some attenuation with increasing depth, it follows that the displacement amplitude of a section of the tubing in the lower portion thereof will necessarily be substantially smaller than in the upper portion if the tubing is of uniform cross-section and material throughout its length. The lower portion of the tubing, however, carries much less load than the upper portion, and may, therefore, be of substantially lighter and more compliant construction.

In accordance with the form of the invention of Figure 1, the power attenuation described in the preceding paragraph is compensated by constructing the pump tubing of an upper relatively thick-walled section 30 coupled as by collar C to a lower thin-walled section 31, the lower section 31 thus having a reduced cross-sectional area as compared with upper section 30. The longitudinal waves of compression and tension (sound waves) which travel down thick-walled high impedance tubing section 30 with comparatively small vertical displacement amplitude of its successive transverse sections will, upon entering relatively lower impedance thin-walled section 31, produce comparatively large displacement amplitude of the successive transverse sections thereof, and the amplitude of vertical oscillation of check valve seat 23 will accordingly be greater than would have been the case had the tubing section 31 been of the same wall thickness as tubing section 30. Such augmented displacement amplitude of the fluid displacing and check valve

means constituted in this case by the valve seat ring 23 and valve ball 25 will quite obviously result in a correspondingly improved pumping rate.

5 Considering the embodiment of Figure 1 in still more particular, it will be evident that the thick-walled pump tubing section 30 may be made up of a number of sections of such thick-walled tubing, all coupled together, as by use of usual coupling collars (not shown) and such a group of thick-walled tubing sections are designated generally by the numeral 30. In like manner, the lower thin-walled portion 31 of the tubing may be made up of a number of tubing lengths of similar construction, coupled together by usual coupling collars (not shown). And it will further be understood that instead of having one relatively thick-walled section and one relatively thin-walled section, additional graduations may be employed if desired. That is to say, there may be more than two tubing sections of reduced wall thickness and/or stiffness in a downward direction, the two here shown being however sufficiently illustrative of the invention.

25 It will thus be seen that even though there be a substantial degree of wave amplitude attenuation between the generator at the top of the tubing and the lower end of the thick-walled tubing section, the wave amplitude will be augmented upon reaching the thin-walled, low impedance tubing section below, thereby increasing the pumping stroke. In some cases, the augmenting of the pumping stroke may necessarily be only sufficient to compensate for wave attenuation. 30 However, as has been made apparent, the scope of the invention is not restricted to compensation of wave attenuation, but on the contrary, by choice of a sufficiently compliant lower tubing section, the vibration amplitude of the pumping member (the check-valved ring 23 of Figure 1) may be made not only as great, but even greater than that occurring within the upper end portion of the pump tubing, immediately adjacent the generator itself.

40 45 Further reduction in the stiffness of the lower tubing section may be accomplished by using a material for the purpose of the lower tubing section which has a lower modulus of elasticity than does the upper tubing section. It will also be evident that a reduction in stiffness of the lower tubing section, in accordance with the aims of the invention, may be accomplished by using for the lower tubing section a material of reduced modulus of elasticity, even though the wall thickness of the tubing remain uniform throughout the upper and lower sections. It is, of course, true that the invention can also be practiced with horizontal pumping, in which event springs 13 are no longer necessary.

55 60 Figure 2 shows the use of a quarter-wave tubing section 40 connecting an upper thick-walled pump tubing section 41 and a lower relatively thin-walled tubing section 42, the connections being made by coupling collars 44 and 45, respectively. The intermediate tubing section 40 is of intermediate wall thickness and stiffness. By having its length a quarter-wave length, measured along the tubing, of a wave generated at the tubing by the vibration generator, impedances are better matched and the transfer of wave energy from the thick-walled to the thin-walled tubing sections is made to occur with improved efficiency.

65 70 Figures 3 and 4 show a modification, employing a relatively short lower tubing section which has been corrugated circumferentially to give it sub-

stantially reduced stiffness (reduced impedance), and consequently very much increased vibration amplitude. In this embodiment the well casing, vibration generator, pump tubing and mounting therefor, may be as in Figure 1, and corresponding reference numerals, but with the suffix *a* added, will be used in Figures 3 and 4 to identify corresponding components. The portions of the pump of Figures 3 and 4 obviously corresponding to Figure 1 will not require further description. Suspended from the lower end of elastic pump tubing 11a is an elastic tubing section 50 which is folded or corrugated in a bellows-like or accordion fashion, thereby greatly decreasing its longitudinal stiffness, as well as the wave-length of a longitudinal wave traversing it. The elastic section 50 is made up of a multiplicity of outwardly-folded bellows sections 51, each flange-connected to the next, and preferably with intervening valve plates 52 having central ports 53 controlled by check valve balls 54.

In operation, the pump tubing 11a will be subjected to longitudinal wave motion of the type previously described in connection with Figure 1 and the lower end thereof coupled to corrugated pipe section 50 will consequently impart corresponding vertical reciprocation, at the vibration frequency of generator Ga, to the upper end of said section 50. Because of the very greatly reduced stiffness per unit length of the corrugated section 50, the latter will, while transmitting the longitudinal wave from its upper to its lower end, be subjected to a vibration amplitude of greatly increased magnitude. Each valve 54 operating in conjunction with the ported valve plate 52 will pump fluid upwardly just as described in connection with Figure 1. On each down stroke, fluid displaced by the downwardly traveling plate 52 will be forced upwardly through passage 53 and past valve ball 54. On each upstroke, the valve 54 will seat, causing the column of fluid to be elevated.

The system of Figures 3 and 4 thus, in common with that of Figures 1 and 2, has the advantage of a magnified vertical oscillation of the valve carrying members, greatly increasing the pumping stroke over what would be accomplished were the valve carrying member to be directly and rigidly connected to the lower end of the pump tubing 11a.

In the embodiment of the invention disclosed in Figures 1 to 4, inclusive, the sound waves are transmitted to the pumping member by way of the pump tubing serving as the elastic wave transmission column. As fully explained in my earlier mentioned application Serial No. 761,456, the wave motion may be transmitted to the pumping member by any suitable elastic column, and for this purpose not only the pump tubing is available, but in many instances a rod string may be employed. Several versions of the latter class are disclosed in my earlier application. Figure 5 of the present case illustrates one embodiment of this general type, and is illustrative of the various types of my pump in which a rod string serves as the wave transmission medium. The pump tubing 80 is suspended within casing 81, the upper end of tubing 80 being screwed into tubing head 82, to which is secured casing head 83. Mounted on tubing head 82 is platform 88 carrying upstanding coil springs 89 whose upper ends support a plate 90 from which is hung suspension rod 91 extending downwardly into tubing head 85, and into the lower end of which is screwed the upper end of elastic sucker rod string

94. A stuffing box 96 surrounds suspension rod 91 and is fitted tightly in platform 88, and the tubing head 85 has production outlets 97 as indicated.

5 The weight of the sucker rod string is thus transferred by rod 91 to plate 90, and thus to strings 89 which are in turn supported through platform 88 from tubing head 82, and the casing head 83 which carries tubing head 82 will be understood to be suitably supported to carry the load thus placed upon it by any appropriate supporting means, not shown.

15 Mounted on the top end of rod 91 is a sound wave generator 100 which may be of exactly the same general character as that disclosed in the previously described figures and hence need not be described in detail. Suffice it to say that this generator, like those previously described, is adapted to generate vibrations in a vertical direction, which are exerted upon the upper end of rod 91, and are thence transmitted to sucker rod string 90.

25 The lower end of rod string 90 is screwed into a fluid impelling and check valve unit 110, which may be of various types, but is here shown in the simple form of a pump plunger 111 having vertical intake bore 112 provided at its top end with a seat for a check valve ball 113, and having upwardly discharging passageways 114 leading from 30 valve ball chamber 115. This plunger may be rigidly secured to the pump tubing, in which case its vertical reciprocation must be participated in by the pump tubing. However, the plunger 111 may also be slidably fitted in the pump tubing, and thus reciprocated vertically relative to the 35 pump tubing walls.

40 In operation, the generator 100 is set into vertical oscillation and transmits longitudinal elastic deformation waves of compression and expansion down the length of the spring-supported elastic sucker rod string 90, the springs 89 oscillating in step with the vibration frequency of the generator, and the waves of compression and expansion being continuously transmitted down the sucker rod string to the check valve and 45 fluid impelling unit 110. It will be understood that the sucker rod portion at the unit 110 will be set into vertical oscillation, and that on each down stroke of the plunger 111, which will occur at an acceleration greater than gravity, the plunger will displace well liquid upwardly through the passageway 112 past the bore 113 and into the 50 valve chamber 115, while on each up stroke of the plunger, the valve ball will become seated and the well liquid in the chamber 115 as well as the liquid column above will be elevated. It 55 should be understood that this operation will occur whether or not the plunger 111 is rigidly secured to the pump tubing. If the plunger is rigidly connected to the pump tubing the only 60 difference is that sufficient power must be transmitted down the sucker rod string to vibrate the lower portion of the pump tubing along with the plunger.

65 As with the other embodiments, the amplitude of the transmitted vibrations becomes attenuated down the elastic column, in this case, the sucker rod string. To compensate for this effect, the sucker rod string is made up to two or more sections, of progressively increasing compliance (reduced acoustic impedance) in a downward direction. Thus the string may comprise an upper section 90a of a certain degree of stiffness, and a lower section 90b of reduced stiffness, the two 70 sections being shown to be joined by coupling 120.

In the present instance, the lower string section 90b has its stiffness reduced by giving it a reduced cross-section. In addition, or as an alternative, the upper section may have a relatively high modulus of elasticity, and the lower section a relatively low modulus of elasticity.

By this means, as in the earlier described forms of the invention, the vibration amplitude of the elastic column at the location of the oscillatory fluid impelling and check valve means, is augmented to compensate for the attenuation which would otherwise undesirably reduce the pumping stroke.

There have now been illustrated several distinct embodiments of the invention. It will be understood that these are not exhaustive, but only illustrative of the broad invention in several of its forms, and that the invention is therefore not to be limited to such forms, but only in accordance with the spirit and scope of the appended claims.

I claim:

1. A deep well pump which includes: an oscillatory fluid impelling pumping member adapted for placement in the well, a sonic wave generator located at the ground surface, and an elastic column of solid material operatively interconnecting said sonic wave generator and said oscillatory fluid impelling pumping member, said column being adapted to transmit alternate waves of compression and tension longitudinally therethrough from said generator to said pumping member, and said elastic column being constructed to have a reduction in stiffness per unit length in a lower portion thereof in order to compensate for wave amplitude attenuation.

2. A deep well pump which includes: an oscillatory fluid impelling pumping member adapted for placement in the well, a sonic wave generator located at the ground surface, and an elastic column of solid material operatively interconnecting said sonic wave generator and said oscillatory fluid impelling pumping member, said column being adapted to transmit alternate waves of compression and tension longitudinally therethrough from said generator to said pumping member, said elastic column including an upper section of a given stiffness per unit length against longitudinal deflection, and a lower section of a lesser stiffness per unit length against longitudinal deflection, whereby to augment the amplitude of longitudinal oscillation of the lower section of the elastic column.

3. A deep well pump which includes: an oscillatory fluid impelling pumping member adapted for placement in the well, a sonic wave generator located at the ground surface, and an elastic column of solid material operatively interconnecting said sonic wave generator and said oscillatory fluid impelling pumping member, said column being adapted to transmit alternate waves of compression and tension longitudinally therethrough from said generator to said pumping member, said elastic column having an upper section of a given cross-sectional area, and a lower section of lesser cross-sectional area.

4. A deep well pump which includes: an oscillatory fluid impelling pumping member adapted for placement in the well, a sonic wave generator located at the ground surface, and an elastic column of solid material operatively interconnecting said sonic wave generator and said oscillatory fluid impelling pumping member, said column being adapted to transmit alternate waves of compression and tension longitudinally therethrough

from said generator to said pumping member, said elastic column having a reduction in cross-sectional area in a downwardly direction.

5. A deep well pump which includes: an oscillatory fluid impelling pumping member adapted for placement in the well, a sonic wave generator located at the ground surface, and an elastic column of solid material operatively interconnecting said sonic wave generator and said oscillatory fluid impelling pumping member, said column being adapted to transmit alternate waves of compression and tension longitudinally therethrough from said generator to said pumping member, said elastic column having a reduction in modulus of elasticity in a downward direction.

6. A deep well pump which includes: a pump tubing of elastic material, an oscillatory check-valved fluid impelling member rigidly secured in the lower portion of said tubing, and a sonic wave generator at the ground surface operatively connected to said pump tubing and adapted to transmit alternating waves of compression and tension longitudinally down said tubing to said fluid impelling member to oscillate the same, said pump tubing comprising an upper section of a given cross-sectional area and stiffness per unit length, and a lower section of lesser cross-sectional area and stiffness per unit length.

7. A deep well pump which includes: a pump tubing of elastic material, an oscillatory check-valved fluid impelling member rigidly secured in the lower portion of said tubing, and a sonic wave generator at the ground surface operatively connected to said pump tubing and adapted to transmit alternating waves of compression and tension longitudinally down said tubing to said fluid impelling member to oscillate the same, said pump tubing comprising an upper section of a given modulus of elasticity, and a lower section of lesser modulus of elasticity.

8. A deep well pump which includes: a pump tubing, an oscillatory check-valved fluid impelling member rigidly secured in the lower portion of said tubing, a string of rods inside said tubing operatively interconnected with said fluid impelling member and extending therefrom to the ground surface, said string of rods having a reduction in cross-sectional area in a downward direction, and a sonic wave generator at the ground surface operatively interconnected with the upper end of the rod string and adapted to transmit alternate waves of compression and tension longitudinally down said string of rods to oscillate the lower end portion of the rod string and said fluid impelling member, said reduction in cross-sectional area of said rod string serving to augment the amplitude of oscillation of the lower end portion of the rod string and of said oscillatory fluid impelling member.

9. A deep well pump which includes: a pump tubing, an oscillatory check-valved fluid plunger slidably mounted in the lower portion of said tubing, a string of rods inside said tubing operatively interconnected with said plunger and extending therefrom to the ground surface, said string of rods having a reduction in cross-sectional area in a downward direction, and a sonic wave generator at the ground surface operatively interconnected with the upper end of the rod string, and adapted to transmit alternate waves of compression and tension longitudinally down said string of rods to oscillate the lower end portion of the rod string and said plunger, said reduction in cross-sectional area of said rod string serving to augment the amplitude of the oscil-

11

lation of the lower end portion of the rod string
and of said oscillatory plunger.
